UNITED STATES PATENT OFFICE.

CHARLES HEINLEY, OF AMITYVILLE, NEW YORK.

DUMPING-WAGON.

No. 919,011.

Specification of Letters Patent. Patented April 20, 1909.

Application filed May 9, 1908. Serial No. 431,748.

To all whom it may concern:

Be it known that I, CHARLES HEINLEY, a citizen of the United States, and a resident of Amityville, in the county of Suffolk and State of New York, have invented certain new and useful Improvements in Dumping-Wagons, of which the following is a specification.

My invention relates to dumping wagons designed to carry and deliver material such as coal and the like; and particularly to wagons of this character in which the material carried is quickly emptied by raising one end of the wagon body and permitting the material to run out the other end through a suitable chute or the like.

It has for its object the more ready and simple dumping of the load.

For this purpose my invention consists of certain novel features of construction which enable the load to be swung at any suitable angle horizontally as well as allowing the load to be raised at one end according to the usual practice.

In the accompanying drawings which illustrate my invention—Figure 1 is a side elevation of my improved wagon, and shows also the wagon body (in dotted lines) in the raised position. Fig. 2 is a plan view of the wagon with the wagon body removed, showing a rotatable support for said wagon body; and also (in dotted lines) said support swung in a horizontal plane. Fig. 3 is a rear elevation of my improved wagon. Figs. 4 to 8 are detail views on an enlarged scale of the guiding arrangement for holding the wagon body in position when raised and lowered. Figs. 9 and 10 are respectively front and side elevations on an enlarged scale of the raising mechanism. Fig. 11 is a partial side elevation on an enlarged scale of the raising mechanism showing the same in unlocked position to permit the wagon body to descend.

Similar characters of reference designate corresponding parts throughout the several views.

Referring to the drawings, 20 designates the wheels of a dumping wagon such as used to convey coal and the like. These wheels carry a frame 21 upon which are two stringers 22, one at each side and approaching each other toward the front of the wagon. These stringers carry a front bolster 23 and a rear

bolster 24 forming with the stringers a stationary frame normally supporting the wagon body 25, said body resting in the bolsters 23 and 24 through front and rear supports 26 and 27 respectively, projecting from said body. The forward support 26 is provided at its lower extremity with an inverted channel shaped piece 28 adapted to straddle the bolster 23, resting upon a metal piece 29 secured thereto. The rear support 27 is provided with an extension 30 adapted to fit the dished portion 31 of the bolster 24. By these means the body 25 readily and quickly locates itself with respect to the frame 21; and further, is locked, in this its normal position, against displacement horizontally, but is perfectly free to move vertically. Means are provided at the rear of the wagon body whereby the said wagon body may be raised to assume an inclined position as indicated in dotted lines, (Fig. 1). This mechanism will be hereinafter fully described.

Mounted upon the stringers 22 and cross-beams 22' is a metallic ring 33'. This ring supports, as hereinafter described, a rotatable, annular guide-way 32 which is designed to carry cross-pieces 35, which in turn carry on each side of the wagon the frame pieces 37 of a second and movable frame. The said guide-way 32 carries between its walls a number of rollers 33 which rest upon the said ring 33', the guide-way being free to turn upon said ring and the rollers 33 providing a roller bearing or support for same. Upon the top of the rollers 33 is placed a ring or table 34 which carries the cross-pieces 35. An annular angle piece 36 fits over the top of the ring 34 as well as the outer wall of the guideway 32, affording a cap to prevent the entrance of dust, small pieces of coal or other objectionable material to the said guide-way. At the forward end of these frame pieces is secured an angle piece 38 having a hole 39 adapted to receive a piece 40 secured to the wagon body 25. The rear ends of these frame pieces 37 carry the raising mechanism, shown on an enlarged scale in Figs. 9 to 11.

As shown in Figs. 9 to 11, a rack 41 is pivotally secured at its upper end to the side of the wagon body 25, one rack being attached to each side (Figs. 2 and 3). These racks engage with respective pinions 42 ro-

tated by a shaft 43 mounted to turn in bearings 44 pivotally secured to the frame pieces 37. A ratchet 45 is mounted on the shaft 43 and operates to turn said shaft through the 5 action of a pawl 46, controlled by an arm 47 and held in engagement with the ratchet 45 through the action of a spring 48. In raising the arm 47, which is loosely mounted on the shaft 43, the pawl slips freely over the teeth 10 of the ratchet and the said shaft is not turned. When the arm 47 is pulled downwardly, the pawl 46 engages the teeth of said ratchet which thereby causes the same to turn, and with it the shaft 43. This rotates the pinions 42 which in turn raise the racks 41 and thereby the wagon body 25. For small loads, viz. up to 2 tons, I prefer to use this means of raising the wagon body, as it is much faster; for heavier loads, it is advisable to 15 employ the usual and well known crank system, which however is considerable slower.

In lifting the wagon body 25 or the load, the arm 47 is raised to about the position shown in dotted lines Fig. 10, and then pulled 20 downwardly as explained; and this is repeated until the load is lifted the desired amount. The ratchet 45 is held during the return of the pawl 46 by a locking pawl 49 engaging 25 said ratchet and pivotally connected to the bearing 44, and held in locking engagement through the action of its weighted end 50. To lower the wagon body, the arm is raised 30 to about the position shown in Fig. 11, the arm 51 having been previously turned by 35 hand to throw the pawl 46 out of engagement with its ratchet 45. In this latter position the pawl 46 throws the locking pawl 49 also 40 out of engagement with ratchet 45, and both pawls thus being free and clear of the said ratchet, allow the same to return and drop 45 the wagon body 25 to its normal position, Fig. 1.

So soon as the wagon body 25 is raised, it is lifted off the bolsters 23 and 24 upon which 45 it normally rests, and is carried by the frame pieces 37, which in turn are carried by the rotatable table 34, the front of said wagon body being carried by the pieces 40 turning in the holes 39 of the angle pieces 38. So 50 soon as the load is thrown off the bolsters and is carried by the table 34, it may be swung horizontally to any desired position convenient for unloading, the table 34 turning freely on the rollers 33. When the 55 wagon body again descends to normal position, the table is relieved of the load which is again taken by the bolsters 23 and 24, the body 25 readily and quickly locating and locking itself as explained.

60 While I have shown the wagon constructed with a specific form of frame, yet I do not wish to restrict myself to the particular frame illustrated, as my invention may be applied to other styles of wagons such, for 65 example, as the platform spring wagons.

I claim:—

1. In a wagon of the character specified: a frame; a movable wagon body normally supported thereby; a rotatable table; a ring secured to said frame; an annular guideway open at the top and bottom; and a number of rollers carried by same and held between the walls of said guideway, said rollers resting upon said ring, and supporting said rotatable table. 75

2. In a wagon of the character specified: a frame; a movable wagon body normally supported thereby; a rotatable table; a ring secured to said frame; an annular guideway open at the top and bottom; a number of 80 rollers carried by same and held between the walls of said guideway, said rollers resting upon said ring, and supporting said rotatable table; and means to cause said rotatable table to carry said wagon body when the rear 85 end of the latter is elevated.

3. In a wagon of the character specified: a frame; a movable wagon body normally supported thereby; means to elevate the rear end of said wagon body; a rotatable table; two side frame pieces carried thereby; an angle piece secured to the forward end of each of said frame pieces and having a hole therein; a pin secured at both sides of said wagon body, registering with said hole, and adapted to locate itself therein and transfer the weight of said wagon body upon the two side frame pieces when the rear of said wagon body is elevated. 95

4. In a wagon of the character specified: a frame; a movable wagon body normally supported thereby; means to elevate the rear end of said wagon body; a rotatable table; a ring secured to said frame; an annular guideway; a number of rollers carried by same and resting upon said ring, said rollers supporting said rotatable table; two side frame pieces carried by said rotatable table; an angle piece secured to the forward end of each of said frame pieces and having a hole therein; a pin secured at both sides of said wagon body, registering with said hole, and adapted to locate itself therein and transfer the weight of said wagon body upon the two side frame pieces when the rear of said wagon body is elevated. 105

5. In a wagon of the character specified: a frame; a movable wagon body normally supported thereby; a rotatable table; two side frame pieces carried thereby; and means to 110 elevate the rear end of said wagon body and comprising racks pivotally carried by said wagon body, pinions carried by said side frame pieces and engaging said racks, a ratchet and a driving pawl, an operating arm for said driving pawl, whereby the said pinion may be rotated and the racks moved, a weighted locking pawl for said ratchet, an arm carried by said operating arm adapted to be turned to throw said driving pawl out of engagement 115

with said ratchet, said arm when in position to unlock said driving pawl forcing the same into position to engage said locking pawl to throw same out of engagement with said 5 ratchet when the operating arm is raised a suitable distance.

Signed at New York in the county of New

York and State of New York this 4th day of May A. D. 1908.
